TUBER

Thomas Earl Coty, Watertown, N. Y.

Application June 1, 1932, Serial No. 614,820

21 Claims. (Cl. 93—19)

My present invention relates to processes and apparatus for forming blanks from a tube to be used in the manufacture of paper bags. It has particular application to so-called "multiwall bags" composed of a number of layers of heavy paper, some of which are formed into a bottom for the bag, the other end being open, or closed with the so-called "valve end". The process in its essential elements consists of cutting-out portions of the inner layers of the multiwall bag, and then assembling the layers into a web and cutting off blanks at the line of the cut-out portions, so that the blanks may be used to form bags of the type shown, for example, in my Letters Patent No. 1,942,019, dated Jan. 2, 1934. Generally the best way of carrying out the process is to assemble all of the plies of paper into a web and then to carry the inner plies through the machine in one plane and the other plies in other planes, and performing the cut-out operation on the inner plies while the plies are separated in this way; then reassembling them into a web which passes to the tuber; after the web is formed into a tube as hereinafter described, it passes on to a cut-out knife which registers with the places in the web where the inner plies are cut off. In passing through the apparatus before it reaches the tuber I arrange means for pasting the plies together so that they may not slip upon one another while they are being formed into a tube. Additional details are hereinafter described.

The apparatus in general consists of a source of supply, usually one or more rolls of paper, depending upon whether a multi-ply bag is being formed or not, generally there being from 3 to 7 plies of the paper; an apparatus for operating upon the inner plies to form the cut-outs; in addition there is feeding means in advance of the apparatus. To obviate a trouble which has sometimes occurred I also employ between the rolls of paper and the apparatus for forming the web additional or auxiliary feeding rolls. In the apparatus for making the cut-outs I also arrange pasting mechanism, and means for removing the cut-out portions of the inner plies from the machines, with means for re-assembling the various plies into a web before that is passed to the tuber. The combination of two sets of feed-rolls in this way is of great advantage, as will be pointed out more fully.

In practice as a rule no difficulty in feeding arises while the machine is running regularly; but if it is necessary to stop it and paste is being applied, the paper softens and warps

from the moisture in the paste; then when the machine is started again, the tension on the paper stretches it and throws it out of registry, or the web may even be torn. The additional or auxiliary feeding rolls interposed between the rolls of paper (it is to be understood that the rolls weigh several hundred pounds apiece, and as already stated, there may be five or seven of them which makes the load at starting very heavy) and these additional rolls take up this load at the time of starting so that all that the rolls in advance of the cut-out apparatus have to do is to draw the amount of paper which is in the machine against the tension, which puts no great strain upon the web. Since the paper may warp or stretch slightly at starting, I provide in the additional or auxiliary rolls interruptions of the circumferences which register with one another once at each revolution, and thus momentarily release the tension and allow the paper to be straightened out by the pull of the advance rollers, thus synchronizing the action of the two sets of rollers upon the web, and making the tension substantially uniform between them. I have found this to be a sufficient provision, but I do not mean to exclude other means of equalizing the traction of the two sets of rolls, since so far as I know that is broadly new.

In the manufacture of the larger kinds of bags the practice has arisen of running the web through printing devices and then rolling it up again upon a mandrel, for use later. When a web thus treated is threaded through a tuber or bottomer it will often be found that the drying of paper in dry weather or the absorption of moisture from the air in damp weather has thrown the print out of registry with the thumb-knife and cut-off knife in the tuber; that is, these knives are apt to mar the print because the bag blank is a little bit shorter or longer than it ought to be. Heretofore it has been necessary to change the sizes of the rolls or to use change gears to vary their relative speeds and bring the blank into engagement with the various circumferences at the proper points. In a parallel pending joint application, Serial No. 582,164, filed December 18, 1931, there is shown a compensator device by means of which the relation of the blank to the bottomers there shown may be determined, and this is well adapted to adjust for registry in the tuber shown in this case, or to change this substantially permanent adjustment while the machine is running.

In practice it has occurred that owing to vari-

ations in the moisture-content of the web or other reasons for its stretching or shrinking, a slight inaccuracy of registry may arise after the machine has been running; while this may be very small, 5 not more than .01 of an inch, it will be clear that when repeated the error is cumulative, and after 100 blanks are cut, amounts to a displacement of one inch, which may completely spoil the registry. To correct any such displacement without stopping 10 the machine, I have devised a form of rectifier or compensator illustrated herein and later more fully described in connection with Figs. 12 to 21 of the drawings. This device is adjustable without stopping the machine so as to 15 add or subtract an amount (usually very small) to the feed at each revolution of the machine, it being understood that a blank is formed and cut off at each revolution. Thus the accurate registry of printed matter on the web with the cut-off 20 may be effected and may be changed indefinitely often by a correction made while the machine is running at full speed; the mechanism is capable of adjusting the registry to .001 of an inch, or even less, in either direction; and as its adjustment may be changed at will, it can compensate 25 for variations in the web which are not capable of correction by any apparatus known to me.

The process described in this case may be carried out by assembling a number of plies into a 30 web, and then separating them so as to get access to the inner plies on which the cut-outs are to be made. It is within my invention of course so to mount the various rolls of paper that the inner plies are already separated from 35 the outer ones and then to proceed with the manufacture. This is an obvious variation which I aim to cover and which does not require separate illustration.

It is also undesirable to have the scraps cut out 40 of the inner plies allowed to remain in the machine, for obvious reasons. I have therefore devised a mechanism which will remove those portions from the machine entirely and may deposit them in a suitable receptacle. The particular 45 device which I have illustrated is purely mechanical in its nature and preferably engages these portions or pieces as soon as they are separated from the web, and may maintain mechanical engagement with them until they are removed from 50 the machine; this I consider the best method of operation, but I do not exclude other means for taking out these pieces and preventing their accumulation.

I have not illustrated and described the particular type of bag which is to be made from the 55 blanks turned out by my improved tuber, because that is shown and described and the method of making it particularly pointed out in Letters Patent 1,942,019.

60 So far as I am advised the present case shows the only tuber which is capable of cutting off the inner layers of the multi-wall bag while maintaining the outer layers at full length, all in a single tuber. This is of great value, and indeed 65 seems to be of controlling importance in commercial production of these bags.

Adjusting registry by a major substantially permanent adjustment, and automatically effecting another correction at each revolution of the 70 machine, as well as the apparatus accomplishing this end, I believe to be new with me.

I have also devised a form of gearing for the knives of my improved tuber, which I believe to be new, and which speeds up the knife at the 75 time of making cuts while preserving the timing

of the entire revolutions so that the cuts are not thrown out of registry by any cumulative error.

The accompanying drawings show an embodiment of the invention.

Fig. 1 is a diagrammatic plan of Fig. 2 and 5 Fig. 2 a diagrammatic side elevation of a machine constructed according to the Figure 1.

Fig. 3 is an improved form of brake for the rolls constituting the source of supply.

Fig. 4 is a side elevation of the rolls of the 10 feeding device interposed between rolls of paper and the operative parts of the tuber.

Fig. 5 is a side elevation of the improved gearing to which I have referred. Fig. 5a shows the construction of the cutters on the roll b^5 , and 15 Fig. 6 is a section on the line 6—6 of Fig. 5.

Fig. 7 is an enlarged detail of one of the gears, with the means of adjusting and securing it in position.

Fig. 8 is a plan of a part of the web when five 20 plies are used.

Fig. 9 is a section on the line 9—9 of Fig. 8.

Fig. 10 is a side elevation, partly in section, of a portion of the cutters used to make the cuts in 25 the web.

Fig. 11 is a conventional perspective of a form of paste-pad which I believe to be new.

Fig. 12 shows a side elevation of the cut-off mechanism, and the compensator mechanism for 30 making corrections of the point of cut-off at each revolution.

Fig. 13 is a plan of the parts shown in Fig. 12.

Fig. 14 is a side elevation of the feed rolls used in connection with the cut-off mechanism.

Fig. 15 is an end elevation of the parts shown 35 in Figs. 12 and 13.

Fig. 16 is an enlarged sectional view of a part of the compensator mechanism.

Fig. 17 is a detail section on a smaller scale on 40 the line 17—17 of Fig. 16 of the means for adjusting the stroke of the compensator.

Fig. 18 is a partial section of a compensator such as is claimed in my joint application, Serial Number 582,164, filed December 18, 1931.

Figs. 19 and 20 are, respectively, a section on 45 line 19—19 of Figure 20, and an end elevation of the ratchet and pawl mechanism operated by the compensator.

Fig. 21 is a detail of the reversing mechanism for the compensator, adapting it to work in either 50 direction.

I will first describe the device with reference to Figure 1, to give a general idea of the arrangement and location of the different instrumentalities.

A designates generally a set of rolls of paper, in this case five being indicated. The rolls which are shown nearly exhausted are marked A^1 . The larger rolls which are mounted for convenient substitution when the rolls A^1 are exhausted, are 60 marked A^2 . The feed mechanism to which I have referred interposed between the operating devices hereinafter described and these rolls bear general reference letter D; the operating devices which cut the slots in the inner plies and apply the paste to the web bear the general reference letter B. The device for making the thumb-cut commonly used in these machines is marked I. The longitudinal pasting mechanism is marked J. The tuber per se, by which I mean the devices for folding over the web into the tube, is marked C. The compensator shown in my prior joint application, which fixes the relation of the cutter to the tube and determines the length of the blank, hereinafter called "the substantially 65

permanent adjustment", is marked H. The feed rolls between the cut-out mechanism and the cut-off which draw the web through the mechanism and tuber per se are marked E; and the 5 cut-off arrangement and ejecting rolls by which the blanks are removed from the machine are marked F. This general arrangement is best understood from Figures 1 and 2. The arrangement of the mechanism for displacing the plies 10 of the web, pasting them and reassembling them in connection with the feed rolls designed to prevent the crushing out of the paste after the assembling is more fully described in Letters Patent to T. E. and A. C. Coty, Number 1,816,361, dated 15 July 28th, 1931.

In Figure 3 there is shown a simple and effective brake designed to prevent the rolls of paper A² from overshooting by momentum if the machine is stopped for any reason, and to give the 20 desired tension. This as will be seen from Figure 3, and also the plan, Figure 1, consists of a canvas strap A⁴, having at its end a weight A⁵. The strap is supported from an arm A³ pivoted at A⁶. When it is desired to change the rolls, as for example when one of them is nearly or quite exhausted, the new roll is placed in position adjacent to the exhausted one, and the arm is thrown over so that the weight A⁵ now presses the strap upon the surface of the fresh roll. The beginning of 25 30 the fresh roll is then pasted on the remnant of the web on the exhausted roll and the latter is cut off behind the joint, after which the machine may be started again.

In Figure 4 I show the method of obtaining the 35 synchronized action of the two sets of rolls, D between the cutting mechanism and the source of supply, and E on the other side of the cutting mechanism, and adjacent to the cut-off device. It is manifest that if the machine be stopped, the 40 pasting mechanism has already applied transverse stripes of paste to the plies constituting the web, and these wet stripes continue to soften the paper until they begin to dry out. This part of the web is then easily stretched or distorted, and if the 45 entire load be carried by the rolls E, drawing against the assembling mechanism at B and the weight of the rolls in the source of supply, it may be considerably stretched or even torn in two. When the load is picked up, however, by the 50 rolls D, these carry the burden of starting the rolls in the source of supply and as the paper is not moist the rolls are started easily, although they are of great weight. Any puckering of the web which may occur between the rolls D and E must, 55 therefore, be taken out in order to avoid waste.

Figure 4 shows the way in which this is done. The rolls D¹, D² constitute one set, D³, D⁴ another. At registering points in the circumference of these rolls, notches d, d, are formed and when 60 these register, the traction is taken up entirely by the rolls E as the web slips between the rolls D, and thus it is straightened out.

The general arrangement of the dispersing mechanism B is shown in our Letters Patent 65 above named. It may be briefly indicated thus: The web W is assembled and then drawn forward by the rolls D. Here the top ply W¹ is carried over rolls at the top of Figure 2; w², the upper inner ply, is carried over similar rolls below w¹, and then carried down again to a point where it may be assembled with other inner plies. A pasting mechanism b¹ applies paste to its under surface. The ply w³ passes through the center of the apparatus shown. The bottom ply w⁵ passes at the 70 75 bottom of the figure; w⁴, the third of the inter-

mediate or inner plies, passes also at the bottom of the figure and then is passed upward, a pasting mechanism b² applying paste to its upper surface. The three inner plies are then assembled and the cutters b⁵, b⁶, presently to be described, 5 cut the openings in these inner plies, which then pass toward the right side of the apparatus; as the upper and lower plies approach the inner plies, paste is applied to their inner surfaces by the mechanisms b³, b⁴, after which all the plies 10 pass the thumb-cut I, which is well known and commonly employed and need not be described, and acts on the lower ply, as shown in dotted lines in Figure 8. At this time the web passes through the longitudinal pasting mechanism J 15 (see Figure 8) which applies paste to the overlapping folds w^{1a} to w^{5a}. The web is then passed through the tuber C, of well-known construction, and folded over on the longitudinal dotted lines shown on Figure 8 into the form shown in dotted 20 lines in the section, Figure 9; after which it passes through the rolls E which are so arranged as not to press upon the pasted seams, as described in our patent already referred to, then passes to the cut-off F and the blanks are cut off and ejected 25 from the machine by the rolls f, f¹.

It is to be understood that in accordance with common practice the rolls referred to, often also called "cylinders", are composed of disks mounted upon a common shaft, and displaced laterally. 30 The rolls E (see Figure 14) are six in number and each set is provided with a cam arrangement so that the rolls of each set are separated as the paste streaks approach, it being so arranged that two of the sets of rolls as shown are always in 35 operation, the rolls lifting as the paste streaks pass through. This arrangement is claimed in Letters Patent to Coty and Coty above named. The lateral spacing of the disks on the shafts also permits the longitudinal streak to pass through 40 without undue pressure, the pull upon the web being usually sufficient to insure adhesion, as the paste dries quickly.

Figure 5 is to be read in connection with Figure 5a, Figure 8 and Figure 10. Figure 8 shows the 45 cuts W² which are made in the inner plies of the web. Figure 5 shows the means for making these cuts and the gearing for operating it. It will be observed that the web W passes between the rolls b⁵, b⁷. The cutters which make the narrow sides 50 of the rectangular cuts are carried by the rolls b⁵, and are marked b^{5a}. The longer sides of the cuts are made by the cutters b^{6a}, carried by the roll b⁶. The construction of these cutters is best understood from Figure 10. It will be understood 55 that they work in the notches shown on the roll b¹¹, and a similar provision is made for the cutters b^{5a} with respect to the roll b¹³. It will be seen that the action of the knives makes the cuts W² in the inner plies of the web. That leaves pieces 60 of these inner plies, of the shape of the cuts, and it is desirable that these be removed from the web to prevent irregularities, and their accumulation in the machine. This is effected by the device shown in Figure 10, consisting of a blade b¹⁴, 65 which is operated by a cam roller b¹⁶ drawn around a stationary cam b¹⁵ as the roll b¹¹ rotates. These pieces are pressed down against the slotted bars b¹⁸ in which the cutters work by a finger b¹⁷ which holds them against the bar until the blade 70 b¹⁴ is pressed against them. The blade b¹⁴ continues its revolution with the roll b¹¹ and holds the cut-out portions while the finger b¹⁷ is drawn away by the rotation of the roll b⁶. At any desired position the blade b¹⁴ may be released by the 75

cam b^{15} and the cut-out portions may be deposited in any suitable receptacle (not shown).

In the right-hand portion of Figure 5 is shown the means for operating the thumb-knife and the gluing devices. The latter are indicated at b^3 , b^4 , and as they are old and well-known it is not necessary to describe them fully. The thumb-knife for making the thumb-cut in the outside sheets of the web, indicated in dotted lines in Figure 8 is marked b^{12} .

The gearing for the two sets of knives illustrated is substantially similar in design. These gears are all eccentric and may be elliptical or off-center, at the designer's option. The construction may be best understood from Figure 6. The centre shaft in that figure is the drive shaft. On the drive-shaft is a hub b^{8a} , and similar hubs are secured to the other two shafts, and are marked b^{7a} and b^{9a} . Loosely mounted to rotate on these hubs are the gears b^7 on the left shaft, b^8 on the right shaft, while on the central shaft are the two gears b^8 , b^{8b} . All of these gears are capable of being independently set or rotated relatively to one another in order to arrange the timing of the cutters as may be desired. It will be seen that by moving the gears b^8 , b^{8b} , relative to one another, the gear b^8 will be rotated by the gear b^8 , and b^7 by the gear b^{8b} , after which they may be clamped in position. This is effected by the plates b^{10} , which are keyed to the respective shafts and are secured to the hubs b^{8a} , etc., by bolts. When the gears have been adjusted to the correct position, that is, when the rolls carrying the knives have been brought to register with each other (as shown in the left-hand part of Figure 5), or when the thumb-knife b^{12} is brought to register with the cut-away portion of the web in the right-hand part in that figure (as indicated in dotted lines in Figure 8), the plates may then be clamped and these will clamp the several gears in their adjusted positions. It will be seen that the plates serve as indexes, a scale b^{23} being formed upon each plate and a fiducial point b^{24} being indicated on the side of the gear, so that any desired setting may be reproduced, according to the length of the bag blank 10 being formed in the tuber. This greatly facilitates the setting of the machine for any desired length of blank.

It will be observed that the arrangement of
50 gearing as indicated, owing to the displacement
of centers, rotates the cutters at an increased
speed at the time when they register with the
slots in the opposing roll and the speed is after-
wards retarded so that the revolution is per-
55 formed at a gradually increasing speed up to the
time that the cuts are made and at a diminishing
speed from then until the knives and slots are
at opposite sides of their revolutions. This facil-
itates the cutting of the paper.

60 Figure 8 has been sufficiently described in connection with the other figures; but it will be seen from Figure 9 in connection with Figure 8 that when the tube is formed from the web, the latter takes the position shown in dotted lines in Figure 9, and the plies at the top of Figure 8 are first folded over and then those at the bottom are folded over upon them, glue having been applied between them so that the closed tube is shown as in Figure 9, as already indicated.

70 In connection with the gluing devices shown somewhat diagrammatically in Figure 5, I employ an improved shoe for applying the glue, which is shown in Figure 11. A hub b^{22} is mounted on the shaft b^{20} . A projecting flange b^{23} sustains 75 a bar b^{24} having a cutaway portion in which the

shoe b^{19} rests, the latter being secured in place by screws and a strip b^{21} . It will be observed that the upper part of the shoe b^{19} is notched so as to provide channels b^{25} in which the paste may run and that these channels, owing to the angle at which they are cut in the face of the shoe, overlap one another, thus making sure that paste is applied over the entire width of the web. 5

Figures 12 and 13, 15 to 17, 19 and 20, are to be read together. They disclose compensating means, which may operate at every revolution to make any correction necessary to bring the bag blank into proper registry with the knives of the tuber. As already stated, very often there is printed matter upon the web and under these conditions, while the registry of the web with the knives may be entirely correct at the beginning of the operation the web itself may be stretched or shrunken at different parts of its length. Under these conditions it is not desirable to alter the setting or registration of the web with the knives by changing the length of the blank except to the extent necessary to bring the blank into registry at each revolution. It is for this purpose that I have devised the compensating device for making those minor corrections. In these figures, G represents in general this particular form of compensator (see particularly Figures 12, 13, and 15). The device G¹⁷ (Figures 15, 19, and 20) is a ratchet and pawl mechanism presently to be described more fully, which is reciprocated by the link G¹⁶, the link itself being operated by an eccentric device G² shown on the right, which is rotated by the sprocket chain G¹¹. As the ratchet and pawl device G¹⁷ is reciprocated, it turns a shaft G³¹ on which is a worm G³⁶, thus rotating slightly the gear F⁴. The compensator H shown in Figure 13 and presently to be described in connection with Figure 18, effects the movement of the shaft upon which the worm-wheel is located with reference to the gear F⁴. Power is communicated to the device by the belt K, but in practice of course any proper form of motor may be used. The shaft G⁵ (see Figure 15) by which the link G¹⁶ is operated, may be approached more or less to the center of the shaft G⁸, as will be described in connection with Figures 16 and 17, thus altering the stroke of the link to any desired extent. The rolls indicated at the top of Figure 15 are the rolls carrying the cut-off knives F¹.

It is obvious that if the relation of the shafts is fixed by the gear wheels, the worm G³⁶ could not be operated without damage to the machine, and it is for that reason that I have introduced here the compensator shown in the joint patent application, Serial Number 582,164, already referred to, and which is illustrated in Figure 18. It will be observed that this same form of connecting device is used in several places in this machine, and as they are all substantially alike, one description will answer for all of them. In Figure 18, therefore, which I describe at this point because it makes it possible better to understand the structure and action of the compensator G, it will be seen that there are two shafts H^{4a}, H⁵, which are co-axial. The shaft H^{4a} carries a hub H², and H⁵ carries a similar hub H³, these hubs abutting against one another and being carried in a casing H⁷. Each of these hubs is geared on its periphery. The hub H² is keyed to shaft H^{4a} and meshes with gears H¹ H¹, the sets of gears H¹ and H⁶ being each upon a common shaft, which is carried by the casing H⁷. The hub H³ meshes with the gears H⁶ H⁶, which are respec-

tively upon the same shafts as the gears H^1H^1 . As the shaft H^{4a} turns therefore it also turns the shaft H^5 at the desired speed ratio with shaft H^{4a} ; but if the casing H^7 be rotated the angular relation of the shaft H^5 and shaft H^{4a} will be altered as the hubs carrying the respective sets of gears H^1, H^6 are rotated about the axis of shafts H^{4a}, H^5 . The casing H^7 is stationary when adjusted, but may be rotated for adjusting the angular relation of H^{4a}, H^5 by the worm-wheel H^8 secured thereto, by means of the worm H^9 .

It will be seen therefore that by using this device in combination with the compensator G the shaft G^{31} may be turned and thus rotate the worm G^{36} turning the worm-wheel G^{37} , which is identical with the worm-wheel H^8 as indicated in Figure 18. I use the letter "H" as generic to this device as it occurs more than once in the machine.

20 The construction of the part of the compensator by means of which the adjustment of stroke is perfected, is best understood in connection with Figures 15, 16, and 17.

25 Referring particularly to Figure 16, there is a shaft G^8 upon which the hub G^1 is keyed. This hub is rotated by the sprocket wheel G^7 driven by the chain G^{11} , Figure 15. It contains an eccentric opening seen in end-elevation in Figure 17, which is filled by a plate G^3 , having a projecting 30 flange G^{3a} , as shown.

35 The central shaft G^8 and the stud shaft G^5 which operates the link G^{16} are shown in dotted lines. It will be seen that the ring G^{14} has internal gear-teeth operated by the gear G^6 on the shaft G^9 . The whole device operates on the shaft G^8 as a center. The worm G^4 is mounted 40 on shaft G^9 and the nut for operating it is contained in the collar G^{12} which is operated by the fork G^{13} (see Figure 13). G^{16a} is a counter-weight for balancing the worm G^4 , for which it also acts as an outer bearing.

45 The device operates as follows: When the handle G^{34} (see Figures 12 and 13) is moved, the fork G^{13} , which is keyed to shaft G^{13a} , swings the collar G^{12} backward or forward on the worm G^{11} , thus rotating the shaft G^9 , and the hub and gear G^6 , adjusting the distance of G^5 from G^8 as a center. This rotates the internally geared ring G^{14} , as will be seen from Figures 16 and 17. The 50 effect of this is to bring the shaft G^5 closer to or further from the center of the shaft G^8 about which the whole device rotates, thus changing the stroke of the link G^{16} . If the shaft G^5 is brought into axial co-incidence with the shaft G^8 , of course there is no reciprocation at all of the 55 link G^{16} . This gives a very close adjustment of the stroke. The adjustment may be approximately effected in the first place by the wheel H^b , which will adjust the axial relations of the 60 shafts H^4, H^5 , shown in Figure 18. If then the shaft G^5 of Figure 16 is in alinement with the shaft G^8 , there will be no reciprocatory motion of the link G^{16} ; while if the handle G^{34} be moved, (see Figures 12 and 13), the shaft G^5 will be 65 displaced slightly from the center, and the link G^{16} will be reciprocated more or less by the action of the eccentric in the hub G^1 , thus turning the shaft G^{31} slightly at each revolution of the device G^2 .

70 Turning now to Figure 1 in conjunction with Figures 12 and 13, it will be seen that there are two of the devices H which I have called "compensators". One of these controls the angular relation of two shafts, only one of them shown in Figure 13, and is there marked H^5 , it being un-

derstood that in accordance with the construction outlined in Figure 18, there are two shafts, H^4, H^5 , the angular relation of which is controlled by the device H shown at the bottom of Figure 13. These devices with which the auxiliary compensator G co-operates to rotate the casing affect by small increments the position of the feed with reference to the cut-off F shown in Figure 12 and in end elevation in Figure 15.

75 As already indicated, the belt K rotates the shaft K^1 and the gear K^2 which rotates the shafts of the compensating device by means of the change-gears K^3, K^4 . These require no extended description because they are old and common, but they determine the rotation of the shafts H^4, H^5 , of the compensator device H . In Figure 13, the cut-off device has been removed for clearness of illustration. The shaft K^1 , Figure 13, also rotates the bevel gears G^2, G^3 , which rotate the shaft H^{4a} , and thus also the shaft H^{5a} of the compensating device H^a . The power transmitted to the shaft H^5 of the compensator H shown in the bottom of Figure 13 through the change-gears drives that shaft and also drives a pair of beveled gears d^1 , which rotate the shaft d^2 .

20 Turning now to Figures 1 and 2 it will be seen that the shaft d^2 operates the feed rolls D , by means of the gears D^5 (the upper part of Figure 1), while the shaft H^{5a} drives the thumb-knife by means of the gears on the left in Figure 1; the slotting knives b^5, b^6 , for cutting out the bottom of the interior plies of the bag; and the various gluing devices shown under the general reference B in Figure 2, as well as the thumb-knife I , and the longitudinal pasting device J of Figure 2.

25 Thus it will be seen that the compensator H^a controls all of the devices between the rolls of paper and the tuber, while the compensator H controls the feed rolls E ; and all of these devices 30 are capable of exact regulation with relation to the cut-off device F ; the compensator H^a being regulated by the hand-wheel H^{10} , Fig. 13, and the compensator H being regulated by its own hand-wheel, and by the incremental adjustment effected at each desired revolution by means of the auxiliary compensator G , the extent of which is 35 regulated by the handle G^{34} of Figure 13. After the position of the casing of the compensator H has been changed until the cut-off knives register 40 correctly with the proper place on the web, the handle G^{34} may be brought to neutral position and the auxiliary compensator G will thus be 45 thrown out of action until some further adjustment becomes necessary by change of conditions 50 in the machine, as by drying out of the paper, which may throw the web out of desired registry.

55 Turning now to Figures 19 to 21, I show the form of clutch device which operates the shaft G^{31} to turn the worm G^{36} and adjust minutely 60 the axial relations of the shafts H^4, H^5 , of Figure 18, without disturbing the main adjustment, the purpose of the action resembling somewhat the coarse and fine adjustment of alinement of a transit glass, for instance. The device is easiest 65 understood from Figure 20, although it is assisted by the construction as shown in Figure 19; and Figure 21 shows separately the reversing mechanism for the clutch. The hub G^{30} is secured to the shaft G^{31} which operates the worm 70 G^{36} of Figure 12, and this hub has a plate G^{17} carrying the pawls G^{18} , of which there may be a greater or less number. I have shown eight, for the purpose of making the action uniform 75 around the circumference. An arm G^{20} is cen-

tered on the shaft G^{35} and the link G^{14} reciprocates this arm to a greater or less extent according to the adjusted relation between the stud G^5 and the shaft G^8 of Figures 16 and 17. On the inside of G^{30} there are ratchet teeth with which the pawls G^{18} co-operate as seen in Figure 20. To prevent the hub rotating backwards under the pull of the pawls due to the friction caused by their springs, I provide a brake G^{32} which presses down on the rim of the hub sufficiently for that purpose, and is provided with an adjustment so that the pressure of the spring may be just sufficient without causing undue friction. It will be seen that the motion of the plate G^{17} and pawls G^{18} is always in the same direction, and is communicated to the shaft G^{31} by means of a gear G^{22} which in the case illustrated, meshes with the gear G^{23} , which in turn turns the gear G^{24} , the latter being on the shaft G^{21} . In order to effect the rotation in the other direction of the shaft G^{31} , I provide an arm G^{21} which carries the two gears G^{23} and G^{25} , which are in mesh. The arm is centered on the shaft G^{23} on which the gear G^{22} is also centered. As illustrated in Figures 20 and 21, with the arm G^{21} in the upper position as there shown, resting against the stop G^{28} and held in position by a stud G^{29} , preferably spring-operated, the rotation of the wheel G^{24} is as indicated by the arrow. When the stud G^{29} is removed to the hole G^{26} , the arm G^{21} is brought to neutral position, so that neither G^{23} nor G^{25} meshes with G^{24} ; when the stud is inserted in the hole G^{27} and brought up against the lower stop G^{28} then the gear G^{25} meshes with G^{24} , and as is obvious the latter gear will run in the reverse direction.

It will be understood that the whole structure shown in Figure 16 rotates as a unit, the worm G^4 rotating around the shaft G^8 , counterbalanced by weight G^{161} .

The method of operation will be obvious from the foregoing description: but I may point out that as the collar G^{12} is moved along the worm G^4 by the handle G^{34} , it turns the shaft G^9 relative to G^8 , thus rotating the ring G^3 and bringing the stud shaft G^5 closer to or removing it from the center around which the shaft G^8 revolves.

I have described the operation of the compensating device G as making an incremental adjustment at every revolution for simplicity of explanation; but as will be apparent from examination of Figure 15, this is true when referring to the revolutions of the shaft G^8 . That shaft may have its ratio to the revolutions of shaft K^1 , the main drive, determined by the ratio between the sprocket upon the shaft H^{4a} and the sprocket G^7 on the shaft G^8 , at anything desired, with reasonable limits. As here shown (in Figure 15) G^8 is rotated about once for every three rotations of K^1 ; but it may be rotated three times or more as often, or less than here shown, giving a precision and flexibility of adjustment which I believe to be heretofore unknown.

I may employ more than one set of the auxiliary feed-rolls bearing the general reference letter D in the location indicated or otherwise, which may be desirable in case of very heavy material or many plies in the web; but as this may be understood from the present showing, I have not deemed it necessary to illustrate and describe it, and I desire my claims to be construed to cover such an arrangement.

What is claimed is:

1. In a machine for forming a tube for multi-

wall bags, means for supplying a plurality of plies; means for separating the inner plies from the outer ones; means for cutting out portions of the inner plies; and means for assembling the plies into a web.

2. In a machine for forming a tube for multi-wall bags, means for supplying a plurality of plies; means for separating the inner plies from the outer ones; means for cutting out desired portions of the inner plies; means for applying paste to one or more of the several plies to secure them together; and means for re-assembling the plies.

3. In a machine for forming a tube for multi-wall bags, means for supplying a plurality of plies; means for separating the inner plies from the outer ones; means for cutting out portions of the inner plies; means for re-assembling the plies; and means for forming a tube therefrom.

4. In a machine for forming a tube for multi-wall bags, means for supplying a plurality of plies; means for separating the inner plies from the outer ones; means for cutting out portions of the inner plies; means for applying paste to one or more of the several plies to secure them together; means for re-assembling the plies; and means for forming a tube therefrom.

5. In a machine for forming a tube for multi-wall bags, means for supplying a plurality of plies; means for separating the inner plies from the outer ones; means for cutting out portions of the inner plies; means for removing the cut-out pieces; and means for re-assembling the plies.

6. In a machine for forming a tube for multi-wall bags, means for supplying a plurality of plies; means for separating the inner plies from the outer ones; means for cutting out desired portions of the inner plies; means for applying paste to one or more of the several plies to secure them together; means for removing the cut-out pieces from the machine; means for re-assembling the plies; and means for forming a tube therefrom.

7. In a tuber for paper bags, a source of supply; means for assembling the plies of paper from the source of supply into a web; means for operating upon the web; feed-rolls for drawing the web through the operating means; auxiliary feed-rolls between the source of supply and the operating means; and means for releasing the grip of the auxiliary rolls at desired times.

8. In a tuber, a source of supply; means for assembling plies of paper from the source into a web; operating apparatus for working on the web; feed-rolls on the apparatus; additional feed rolls between the supply source and the apparatus; and means for permitting lost-motion between one of the sets of rolls and the web so as to synchronize the action on the web of the two sets of feed-rolls.

9. In a tuber, a source of supply; means for assembling plies of paper from the source into a web; operating apparatus for working on the web; feed-rolls in advance of the apparatus; additional feed-rolls between the supply source and the apparatus; and means for synchronizing the action on the web of the two sets of feed-rolls, such means interrupting the traction of the rear set of rolls sufficiently to permit the advance rolls to take up any slack between the two sets.

10. In a tuber, a source of supply; an apparatus for acting upon the web furnished by the source of supply; feed-rolls in advance of such

- apparatus; and additional feed-rolls located between the source of supply and the apparatus, such additional rolls having circumferential interruptions permitting the momentary release of the traction upon the web to allow the advance rolls to take up any slack in the web; the additional rolls also acting to take the drag of the supply source from the advance rolls, and prevent stretching of the web.
11. The process described of forming a tube for making multi-wall bags, which consists in assembling a number of superposed plies into a web; separating the outer plies from the inner ones; cutting out portions of the inner plies; and then re-assembling the plies.
12. The process described of forming a tube for making multi-wall bags, which consists in assembling a number of superposed plies into a web; separating the outer plies from the inner ones; cutting out portions of the inner plies; and then re-assembling the plies; pasting them together and folding them into a tube.
13. The process described of forming blanks for making multi-wall bags, which consists in assembling a number of superposed plies into a web; separating the outer plies from the inner ones; cutting out portions of the inner plies; re-assembling the plies; pasting them together; folding them into a tube; and cutting off blanks from the tube.
14. The process described of forming a tube for making multi-wall bags, which consists in assembling a number of superposed plies into a web; separating the outer plies from the inner ones; cutting out desired portions of the inner plies while they are separated from the outer ones; re-assembling the plies and forming a tube therefrom.
15. The process described of forming a tube for making multi-wall bags, which consists in assembling a number of superposed plies into a web; separating the outer plies from the inner ones; cutting out desired portions of the inner plies while they are separated from the outer ones; pasting the plies during the re-assembling and forming a tube therefrom.
16. The process described of forming a tube for making multi-wall bags, which consists in assembling a number of superposed plies into a web; separating the outer plies from the inner ones; cutting out desired portions of the inner plies while they are separated from the outer ones.
17. The process described of forming a tube for multi-wall bags, which consists of segregating the inner plies from the outer ones; cutting out desired portions of the inner plies; then assembling the inner and outer plies into a web and forming a tube therefrom.
18. In a tuber for multi-wall bags, means for segregating the inner plies of paper from the outer ones; means for cutting out desired portions of the inner plies; means for assembling all of the plies into a web; and means for forming a tube from the web.
19. The method of forming a blank for a cut-out bottom multi-wall bag, which consists of segregating the inner plies of the web from which the blanks are formed from the outer plies; cutting away portions of the inner plies at the parts from which the bottom is to be formed; assembling the plies into a web and securing them together; forming the web into a tube; and cutting off the blank from the tube at the position of the cut-away portions of the inner plies.
20. Means for preparing a blank for a cutout bottom multi-wall bag, comprising means for segregating the inner plies from the outer ones; means for cutting away portions of the inner plies at the parts thereof from which the bottom is to be formed; means for assembling all of the plies into a web; means for forming a tube from the web; and means for cutting off a blank from the tube at the position of the cut-away parts of the inner plies; the said several means all operating automatically and successively upon each blank.
21. In a tuber for paper bags, a source of supply; means for assembling plies of paper from the source of supply into a web; mechanism for operating upon the web; feed rolls for drawing the web through the operating means; auxiliary feed rolls located between the source of supply and the operating means, such auxiliary rolls acting to relieve the strain on the web at starting; and means for releasing the traction of such auxiliary rolls upon the web at desired times, so as to permit the other feed rolls to take up any slack in the web between the two cooperating sets of feed-rolls.

THOMAS EARL COTY.
